UNITED STATES PATENT OFFICE.

HARRY BERNARD JONES, OF CHICAGO, ILLINOIS.

GRANARY.

Application filed October 15, 1923. Serial No. 663,770.

My invention relates to granaries, and has for its principal object the provision of a new and improved form of construction which shall be so arranged as to provide 5 the desired housing space on opposite sides of a central drive way, and which shall be of such strength as to support a large amount of ear corn in one or more portions or sections and a large amount of small 10 grains in one or more other sections, the structure being so designed and arranged as to have the maximum strength and reinforcement for resisting the pressure of the contents in proportion to the size of the 15 several parts making up the structure, and being arranged so as to be capable of being built for a minimum expenditure of materials and labor.

A further object of the invention is to 20 provide a granary or corn crib structure including several bins and cribs formed with walls built up of flat, relatively thin cement slabs or staves with some of the walls 25 arcuate in plan, and bands passing about the slabs in these arcuate walls on the outer surfaces thereof for maintaining the same in position and for absorbing all outward pressure thereagainst, and with all of such 30 bands tied to a single suitably disposed framework, to prevent outward collapse of such walls and to prevent also distortion of the same as the contents behind these walls shift from time to time.

It is another object of my invention to 35 improve devices of this type in sundry details hereinafter pointed out. The preferred means by which I have accomplished my several objects are illustrated in the accompanying drawings and are hereinafter specifically described. That which I believe to 40 be new and desire to cover by Letters Patent is set forth in the claims.

In the drawings—

Fig. 1 is a central vertical section, partly 45 broken away, through one of the forms of my improved granary.

Fig. 2 is a horizontal section through the granary of Fig. 1, being taken substantially at the line 2—2 of Fig. 1.

Fig. 3 is an enlarged detail view, illustrating in detail a small section of the wall in its preferred form.

Fig. 4 is an enlarged detail view showing the preferred construction at the point

where the inner and outer wall portions are 55 joined.

Fig. 5 is a horizontal cross section similar to Fig. 2, but showing a modified form of construction; and

Fig. 6 is another view similar to Fig. 2, 60 but showing still another modified form of construction.

Referring to Figs. 1 to 4, in which corresponding parts are indicated by the same reference characters, 10 indicates a foundation and floor of concrete or other suitable material upon which is built a substantially circular granary or bin section 11. At opposite sides of the section 11, I have provided other sections or cribs 12 and 13 70 formed by the use of arcuate wall portions, as is best shown in Fig. 2, the sections 12 and 13 being also carried by the foundation 10.

As is best shown in Fig. 3, the arcuate 75 wall portions by which the sections 12 and 13 are provided are built up of flat, relatively thin slabs or staves 14, preferably made of concrete or other suitable hard material, the joints between the slabs being 80 broken throughout the wall structure, as is shown in said Fig. 3. The slabs 14 are preferably perforated to provide for suitable ventilation of the granary, the openings 15 through the slabs being preferably so arranged 85 as to prevent the entrance of rain or snow under normal conditions, and being of such a size as to prevent the entrance of rats. Retaining bands 16 are provided about the slabs 14 for holding the slabs in tightened 90 relation to one another. In Figs. 1, 2, 5 and 6, I have not shown the detailed construction of the slabs, and the size of the bands 16 has been slightly exaggerated in order better to illustrate the construction. 95

The wall of the section 11 is formed of slabs 17, preferably similar to the slabs or staves 14, except that the slabs 17 are preferably solid without the openings 15 therethrough. The slabs 17 are held in position 100 by retaining bands 18.

The central section or bins 11 of the granary is shown as open at diametrically opposite points for providing a driveway therethrough, the slabs 17 of the wall portions at 105 the ends of such portions being built up in connection with a single frame including, in the form shown, heavy I-beams 19 through

- the webs of which the retaining bands 16 and 18 are passed, as is best shown in Fig. 4, such bands being threaded upon their ends to provide for tightening, by the use of nuts 5 20. Other vertically disposed I-beams 21 are interposed in the circular wall portions comprising the lower part of the section 11, the slabs 17 being embraced snugly by the flanges of the I-beams 21, with the retaining bands 18 passing about the outer faces of the I-beams.

At each end of the driveway, the I-beams 19 are connected by a curved horizontally disposed I-beam 22 which serves both as a 15 tension member between the I-beams and also as the support for the superposed wall portion 23 (see Fig. 1), such wall portion 23 being formed as a connection between the side portions so as to form a continuous annular wall above the driveway.

At each side of the driveway, the I-beams 19 are connected by a horizontally disposed I-beam 24, which serves as a tension member between the vertically disposed beams 25 19, as a support for a floor, as hereinafter described, and as a brace member between the side portions of the wall forming the section 11, also as hereinafter described.

The desired bracing between the side portions of the wall of the section 11 is provided by I-beams 25 interposed between the beams 24 and the upper ends of the vertically disposed I-beams 21. As will be seen from Fig. 2, the I-beams 21 in the construction there shown are spaced at substantially equal intervals circumferentially between the large I-beams 19, and the beams 25 at each side converge slightly toward the longitudinally extending beam 24. For supporting the beams 24 at opposite sides of the driveway with respect to the inward pressure thereon by the beams 25 I have provided a transversely extending I-beam 26, as clearly shown in Fig. 2. Posts 27 40 are preferably provided underneath the inner ends of the inwardly extending beams 25. A floor 28 of any suitable type is mounted by means of joists 29 upon the horizontally disposed beams 24, 25, and 26 45 within the section 11, the posts 27 serving to assist in supporting the load carried by the floor 28.

In the construction shown, partitions 30 are provided above the floor 28, dividing 50 the section into four bins, the partitions 30 being indicated by dotted lines at the points where the floor 28 is broken away.

An elevator 31 of any approved type is provided at one side of the driveway, such 60 elevator being indicated merely diagrammatically. Drag openings 32 are provided in the floor to permit the insertion of the drag of a corn sheller or other suitable conveyor, boards 33 being provided for closing 65 the openings 32 under normal conditions.

Doors 34 are provided through the outer walls above the drag ways 32 for affording access to the dragways as may be desired. A roof 35 of any suitable type is provided above the whole structure comprising the 70 sections 11, 12 and 13. As will be readily understood, the retaining bands 16 at the top portions of the walls forming the sections 12 and 13, are the same as the retaining bands 16 at the bottom portions of said 75 walls, terminating at the I-beams 19, as above described. The retaining bands at the upper portion of the sections 11, however, are different from those at the lower portion, such bands at the upper portion being 80 extended clear about the section rather than being terminated at the I-beams 19. The retaining bands at the top are accordingly indicated by the numeral 36.

By my construction, I have provided a bin for small grain above the central driveway within the section 11, and have provided suitable retainers or cribs for ear corn within the sections 12 and 13. By the provision of the bracing means comprising the I-beams 24, 25, and 26 and the partitions 30 between the side walls of the section 11, I have provided for efficient bracing of such side wall portions with respect to the inward pressure thereon by the corn within the sections 12 and 13. By the provision of the tension members 22 and 24, between the several vertical I-beams 19, I have made the whole structure substantially a unit so as to have the maximum strength and maximum 95 stability. By making the wall portions arcuate or substantially circular, I have provided for making the cost of production as low as possible in proportion to the size and capacity of the structure. Also by tying 100 all of the various arcuate walls to a single frame, I have provided an exceptionally strong structure and one in which all outward thrust of the contents against the walls 105 will be transmitted through the bands to the framework and thus prevent displacement of the walls from normal position, which sometimes happens when the load is unevenly bearing against the walls of said 110 structure. By providing a driveway of considerably greater width at its central portion than at the ends thereof, I have provided ample space for the disposition of the machinery which it may be desired to mount 115 within the granary.

In the construction shown in Fig. 5, the central section 11 is similar to the central section 11 of the form above described, in a general way, the principal difference being that the substantially circular wall portions forming the central section 11 are oppositely disposed but not concentric with each other.

Other slight differences will be noted, such as the use of straight I-beams 37 across the driveway at its ends to serve as tension 130

members between the large I-beams 19, the use of two brace members 38 between the longitudinally extending beams 24, and the use of I-beams 39 extending clear to the top 5 of the central section 11 in lieu of being terminated at the floor above the driveway, as in the construction of Fig. 1. It will be appreciated, of course, that the retaining bands 18 at the top portion of the central 10 section 11 are the same as those at the bottom portion, being terminated, in the construction shown in Fig. 5, at the large I-beams 19 rather than being extended clear about the structure, as at the top of the central 15 section 11 of the construction shown in Fig. 1.

In the construction shown in Fig. 6, a central section 40 is provided, substantially cylindrical in form. In this construction, 20 the intermediate I-beams 21 are omitted, but the general form of the section 40 is otherwise quite similar to that of the section 11 of Fig. 2. The outer sections are formed by the use of substantially circular concentric wall portions, this arrangement making necessary other provisions for connecting the end portions of the outer, circular wall portions. In the construction of Fig. 6, 25 large I-beams 41 are provided at opposite sides of the driveway for the section 40, and large I-beams 42 are provided at the ends of the driveway in the outer concentric wall portions. For completing the sections 43 and 44 at opposite sides of the central section 40, longitudinally extending wall portions 45 are provided between the oppositely disposed ends of the inner and outer concentric wall portions. The vertical I-beams at each side of the drive-way of the central 30 portion 40 are connected by tension members 46, in the form of I-beams, and curved I-beams 47 serve as tension members between the vertically disposed I-beams 41 at each 35 end of the driveway, which tension members also serve for supporting the upper portions of the wall of the central section 40 above the driveway, such sections of wall being indicated by the numerals 48. The vertically disposed I-beams 42 at each end of the 40 driveway are connected by curved I-beams 49, which serve as tension members, and also as the means for supporting the wall portions 50 above the driveway. Longitudinally extending tension members 51 are 45 provided above the wall portions 45 serving to connect the vertically disposed I-beams 41 with the corresponding vertically disposed I-beams 42.

It will be understood that the central section 40 has its wall made up of slabs 52 tightened with respect to one another by means of retaining bands 53 which, at the top of the section 40, extend clear about the central section 40, and at the bottom are 55 terminated in and adjustably secured to the

vertically disposed I-beams 41. In like manner, the walls of the sections 43 and 44, are made up of slabs 54 tightened with respect to one another by retaining bands 55 which, at the upper portion of the structure, extend clear about both sections 43 and 44, and which at the lower portion are terminated in the vertically disposed I-beams 42, in the manner above described in connection with the remaining structures. 75

While I prefer to employ the forms of structure shown and above described, it will be understood that I do not desire to limit myself to the use of the detailed constructions illustrated, except so far as such detailed constructions are specifically claimed, inasmuch as it is evident that various changes might be made in the construction without departing from the spirit of my invention. 85

I claim:

1. A granary comprising a section in the form of a cylinder, other sections formed of arcuate wall portions extending about the cylindrical section at opposite sides thereof and secured at their ends to the cylindrical section, tension members connecting the ends of one of said arcuate wall portions with the ends of the other arcuate wall portion, the walls of said sections being composed of relatively flat and thin staves, and bands surrounding said walls on the exterior thereof for retaining said staves in position. 90

2. A granary comprising a section substantially in the form of a cylinder, other sections formed of substantially segmental circular wall portions extending about the cylindrical section at opposite sides thereof and secured at their ends to the cylindrical section, tension members connecting the ends of one of said segmental circular wall portions with the ends of the other segmental circular wall portion, and other tension members each extending across the cylindrical section and connecting the opposite ends of one of said segmental circular wall portions. 100

3. A granary comprising a substantially segmental circular wall portion made of slabs, upright beams at the ends of said wall portion, tension bands extending about said slabs and secured to said beams, a second segmental wall portion made of slabs extending about said first named wall portion, and other tension bands extending about the slabs of said second wall portion and also secured to said beams. 115

4. A granary comprising a substantially segmental wall portion made of slabs, vertically disposed steel beams having flanges embracing the slabs at each end of the wall portion, bands extending about said slabs and secured at their ends to said beams for maintaining said slabs in position, a second substantially segmental wall portion made of slabs extending about said first named 125

wall portion and terminating also between the flanges of the beams, and other bands extending about the slabs of said second wall portion and secured at their ends to 5 said beams.

5. A granary structure having a plurality of storage compartments formed by walls which are curved in plan so disposed with respect to one another that the curve 10 defining one wall intersects a curve defining another wall, and the ends of said walls terminating at said points of intersection, said walls being composed of relatively flat and thin staves of concrete, a frame for a portion of said structure having uprights disposed at the points of wall intersections, and bands passing around said wall for retaining the staves in position therein, said bands being secured to said upright frame member at the points of wall intersections. 20

6. A granary consisting of a plurality of curved walls arranged to intersect thus defining a plurality of storage compartments, a frame for said granary having uprights at 25 the points of wall intersections, said walls

being formed of relatively flat and thin staves arranged in edgewise relation in courses, bands passing about the convex surfaces of said walls and having the ends thereof secured to said frame upright for 30 preventing collapse of said walls outwardly, and tension members connecting certain of said uprights. 35

7. A granary consisting of a plurality of curved walls arranged to intersect thus defining a plurality of storage compartments, a frame for said granary having uprights at the points of wall intersections, said walls being formed of relatively flat and thin staves arranged in edgewise relation in 40 courses, bands passing about the convex surfaces of said walls and having the ends thereof secured to said frame uprights for preventing collapse of said walls outwardly, and tension members connecting certain of 45 said uprights, said frame being arranged to define an opening through a portion of said structure.

HARRY BERNARD JONES.
